CLAIM

The ornamental design for a fluid turbine mixing rotor blade, as shown and described.

DESCRIPTION

FIG. 1 is a front right side perspective view of a fluid turbine mixing rotor blade, showing my new design;

FIG. 2 is a rear left side perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.
